BUILDING AND BUILDING CONSTRUCTION

Robert C. Lafferty, New York, N. Y.

Application February 21, 1938, Serial No. 191,749

6 Claims. (Cl. 72—1)

My invention relates to improvements in buildings and building construction and it is particularly adapted for use in buildings of the prefabricated type.

5 The economical advantages of factory made buildings is recognized, but efforts heretofore made to provide a satisfactory building of this type have been unsuccessful.

An object of the present invention is to provide 10 an improved, useful and novel building which will overcome the objections and defects existing in known structures of this type.

A further object of the invention is to provide 15 novel means for minimizing the time, mechanical operations, and expense required for manufacturing, transportation, delivery and erection in building construction.

A further object of my invention is to provide 20 means for insulating a building against changes in temperature and the transfer of heat to and from the interior.

A further object of my invention is to provide proper weatherproofing in a building.

25 A further object of my invention is to provide new and useful means for sealing the walls of a building against the admission of moisture while providing controllable ventilation means.

A further object of my invention is to provide 30 a building which is fireproof.

35 A further object of my invention is to provide a building having pre-formed parts.

A further object of my invention is to provide a new and useful method for constructing buildings.

40 A further object of my invention is to provide in a building new and useful structural features and improvements.

A further object of my invention is to provide 45 in a building new and useful means for strengthening the walls thereof.

A further object of my invention is to provide a new and useful structural element adapted for use in floors, walls and other parts of buildings 50 and which is superior to those heretofore used.

A further object of my invention is to provide a new and useful reinforced structural element for use in buildings.

55 A further object of my invention is to provide a ventilated structural element for use in buildings.

A further object of my invention is to provide a structural element in which no wood or other herbiferous material is used.

60 A further object of my invention is to provide

in a building efficient and dependable metal to metal wall, floor, roof and corner joints.

A further object of my invention is to provide a building unit having pre-installed conduits for electric wiring and the like.

A further object of my invention is to provide a building having suitable and attractive window and door apertures.

A further object of my invention is to provide 10 a wall unit for use in buildings which will adapt itself to a great variety of pictorial or architectural indented or embossed designs.

A further object of my invention is to provide new and useful roof means in a building.

A further object of my invention is to provide 15 in a building new and useful gutter means.

A further object of my invention is to provide means for harmonizing with a building structure the rain water leaders and the like.

A further object of my invention is to provide 20 a new and useful window for a building.

A further object of my invention is to provide a new and useful mold for forming building elements.

A further object of my invention is to provide 25 new and useful means for casting or forming structural elements for use in buildings.

A further object of my invention is to provide a new and useful means for constructing a building element.

A further object of my invention is to provide 30 new and useful means for forming a building element having a contained grid.

A further object of my invention is to provide new and useful interior partitions for use in 35 buildings.

A further object of my invention is to provide composable building modules which will lend themselves to individualistic and multiple assembly in structures of various sizes.

A further object of my invention is to provide 40 a building module of a predetermined cubical content, which may be united with similar units or modules in a building of attractive architectural design and will adapt itself to the introduction of variations in form, color, texture and other architectural features.

The accompanying drawings illustrate in a diagrammatic manner preferred embodiments of my invention, but it is to be understood that 50 changes and modifications may be made therein without departing from the spirit of my invention and that I do not intend to limit myself to the particular forms shown.

Figure 1 is a diagrammatic representation of 55

a building unit or module, partly assembled, the side walls being shown in assembled position, the roof section being suspended and about to be placed on the side walls, a corner plate being 5 also shown suspended and about to be set;

Figure 24 is a diagrammatic view of an interior 60 partition and

Figure 25 is a detail of a portion of a door.

Similar characters of reference refer to like parts throughout the several views.

My improved building comprises one or more 65 module apartment or room units which are preferably of uniform size and which may be combined or assembled attractively and as may be desired into a multiple-unit structure or may be used singly as separate, complete and independent 70 buildings.

When two or more apartment units or modules are combined, I prefer to provide a single dividing wall between adjoining units.

The side walls, floor and roof of the respective 75 apartment units comprise individual pre-formed

parallelopiped panels or slabs which are constructed in the manner hereinafter described.

These panels or slabs are constructed in like manner, with such variations in form as may be required or convenient for the intended use. 5 For example, the side wall slabs or panels will be formed with suitable window and door apertures; the floor slabs or panels may be formed with stair wells and the like, when such openings are called for; the roof slabs will be formed with 10 suitable chimney openings, vents and the like as may be desired, and the upper surface thereof may be convexed to provide for drainage and the like. The interior partitions may be of a lighter construction than are the weight supporting 15 walls.

While, therefore, the slabs or panels are not necessarily of counterpart form, they are each constructed according to my novel method as hereinafter explained and possess substantial 20 identity of structure.

My improved apartment unit module preferably comprises a cell or room having floor, side walls and roof, each constructed according to my herein described method but it will be apparent 25 that my units or slabs may be used in combination with a floor or foundation, roof and other parts constructed in any desired manner, without departing from the spirit of my invention and that my individual panels or wall elements may 30 be used in any manner and for any purpose.

My improved parallelopiped panel or slab comprises a pair of spaced face plates 1 and 2 of concrete or the like in combination with an intermediate spacing and reinforcing grid or frame as hereinafter described therebetween and anchored in the said side plates. Non-inflammable insulating material 3 is provided within the panel and between the said face plates and is preferably supported against packing by integral marginal anchorages 4 thereof with the adjacent face plates and may be further supported by suitable tongues or the like 5 provided for that purpose.

The panels or slabs which form the side walls of the structure are preferably of a standard or 45 uniform size, which may be approximately nine feet by twenty-eight feet in area, or as may be desired, and are preferably prefabricated at a factory located within convenient transportation distance from the building site where they are to 50 be assembled and erected. The floor and roof panels or slabs are approximately twelve by twenty-eight feet in area and are also preferably prefabricated at the same factory where the panels for the side walls are constructed but, as above explained, any floor or roof construction may be used with the prefabricated side walls, and any wall construction may be used with the prefabricated floor or roof construction.

The reinforcing grid or frame which serves as 60 a strengthening and spacing member for the slab or panel, is preferably formed of a plurality of counterpart metal channels 6, the marginal edges of which are turned inwardly, forming reentrant flanges 7, and which are preferably arranged back to back and welded or otherwise tied together, and form the lateral cross members of the grid, in combination with longitudinal stiffening angles 8, to which the lateral members are welded or otherwise secured. The longitudinal channels 8 70 are preferably laid at the longitudinal sides of the grid.

I do not intend, however, to limit myself to the use of double or back to back channels although 75 this is preferable where strength is a desideratum.

The channels may be modified in shape and may be used singly as illustrated in Figure 10.

Upon the underside of the grid thus formed, there are affixed a plurality of small rods or wires 9, which form a web bound to the grid by tangs 10 cut out in the channels 6 and bent over thereon.

In forming the said grid, suitable provision will be made therein for door and window openings as illustrated at 11 in Figure 10 and such 10 other configuration of the completed slab or panel as may be called for by the architectural designs for the building to be constructed.

The grid, thus formed and constructed, is now ready to be anchored in the side or face plate 1 15 of the slab or panel, which is cast in a mold comprising a bed 15 and vertically adjustable side walls 16, carried by a suitable carrier 17 having traction wheels or rollers 18 running in guide tracks 19.

20 The side walls 16 of the mold are vertically adjustable with relation to the bed 15 by means of jack screws 20 or the like and stops 22 may be provided.

The depth of the mold, being adjusted as required for the work, there may be formed on the bed 15 a matrix 23 of clay or the like in which may be molded or formed such shapes as may be desired to impart ornamentation to the face of the plate to be cast.

30 There is then introduced into the mold, the cement mortar, which is to form the skin or facing 25 of the side plate 1 and which is preferably of a superior quality of dense Portland cement and sand, which may be colored as desired by 35 suitable pigment.

The facing material is preferably carried up on the side walls 16 of the mold as at 25' (Figure 6) so that the completed slab or plate will be properly faced on all exposed parts.

40 The filling of concrete or the like 26 is now introduced and the mold filled level with the top of the side wall 16 and is leveled off with a screed 27 or the like.

While the material in the mold is still in a 45 plastic state, the grid formed as above described, with its attached web 9, is lowered to the plastic mass and pressed downwardly therein, being vibrated meanwhile either manually or mechanically until the downward marginal portion of the 50 grid is sunk into the plastic plate 1 a sufficient distance to cause the same to be firmly and securely anchored therein when the plate hardens.

The grid should be of such dimension that it will closely fit into the walls 16 of the mold 55 whereby the plastic material of the plate 1 will not work up over the side walls 16 but will enter and form clenches with the channels 6 and 8 through the apertures 12 therein.

It is important that the grid and its attached 60 web 9 be so vibrated that the cement or concrete 26 will thoroughly and completely engage all of the immersed surfaces thereof and the vibration should be continued until the grid and webbing 9 is integrated with the material of the plate.

65 Stops 38 (Figure 10) may be provided whereby the grid will be immersed in the cement to the desired depth.

When the grid has been properly set in the plate 1 as above described, the pallet 15 with its 70 load of plate and integrated grid is moved on the carrier 17 and rollers 18 to a suitable location where flexible electric conduits 36 may be threaded through suitable apertures 14 in the grid channels 6 and 8 and electrical outlet boxes 37 and 75 the like may be applied as may be called for by

the architectural plans and spot welded or otherwise secured to the grid. These outlet boxes 37 should be so positioned that their outer surfaces will project above the grid to approximately the outer plane of the plate 2 to be placed thereon as 5 hereinafter explained.

The spaces between the channels 6 of the grid are then filled with suitable insulating fibres 3 which should be so placed that marginal portions 4 thereof penetrate and engage the adjacent surface of the wet concrete of the adjacent plate 1 and project above the upper plane of the grid sufficiently to penetrate and engage with the wet concrete of the plate 2 to be applied to the grid as hereinafter described, whereby ties will be formed 15 between the insulating material 3 and the plates 1 and 2 which will hold the insulation in place when the concrete plates 1 and 2 are set and dried and when the slab is in vertical position. Supporting tongues 5 may also be provided on the 20 channels 6 to enter and retain the insulating fibres 3 in position and to prevent packing thereof.

A second layer of webbing 9 is then placed over the insulating material 3 and secured to the channels of the grid by tangs 10 thereon as above 25 described.

The partially formed panel or slab is then allowed to set and dry and is conveyed to a suitable location adjacent to a second facing plate 2 prepared to receive the grid and plate 1 which 30 second plate 2 is prepared as above described with respect to the first mentioned plate 1. The grid with its first plate 1 anchored thereto is then raised and turned over upon the said second plate 2 which is in a wet and plastic state, and 35 the grid is sunk into the said second plate 2 to a predetermined depth which will be measured by the gauges 38 as shown in Figure 10. The grid is then vibrated as above described with respect to the first plate 1 and the grid is thoroughly 40 integrated with and anchored in the said second plate 2 until the concrete has been firmly and effectively clenched through the apertures in the grid.

The casting and formation of the panel unit or parallelopiped is now completed and the same is 45 conveyed to a curing room and properly cured.

I prefer to stand the said slab or panel unit on edge in vertical position during the curing process and to spray the exposed surfaces thereof at suitable intervals, with warm water and warm moist air or steam, exercising care to avoid moistening the inner portion of the grid or of the insulating material within the slab.

When the slab or panel has been properly 55 cured, it is transported to the field or building site where it is to be used or erected.

At the building site, a suitable foundation is prepared for the building, which may include piers 39, or the like.

The slabs are preferably provided with marginal brackets 41 which are welded or otherwise secured to the marginal channels of the slab grid, and holes or seats 41' are formed in the said brackets which form convenient holds for the tackle by which the slabs are raised and placed in position.

A suitable mortar bed being laid on the pier 39 of the foundation, the marginal brackets 41 of the floor slab are set thereon, as illustrated in 70 Figure 13.

The floor slab, having been thus placed in position on the foundation, the side walls are erected at the marginal edges of the floor slab, in vertical position, as shown in Figure 1, and the roof 75

slab is then swung into position and set on the vertical wall slabs.

It is not necessary that both plates of the slabs be of equal thickness and I prefer to provide a slab in which one of the surface plates is thicker than the other.

In the use of the wall-slab plates, I prefer to use the thicker plate as the exterior plate. Where the slabs are used for floors, I prefer to use the thicker plate as the wearing or exposed surface and where the slabs are used for the roof, I prefer to use the thicker surface of the slab for the roof surface.

The slabs are so shown in Figure 13.

15 There may be cast in the floor slab, a sheet of linoleum 28 or the like.

It is desirable to avoid lightly sealed air spaces within the walls and I, therefore, prefer to provide air vents 43 in the mortar bed 42 whereby controllable quantities of air may be admitted to the interior of the slabs to circulate therethrough. These air vents 43 in the mortar bed may be conveniently formed by placing thin boards or forms in the mortar bed and extending therethrough, which may be withdrawn after the mortar is laid and the wall is in position. These vents 43 may be adjusted to the existing conditions and may be readily sealed or closed when desired.

30 In assembling the structure, I prefer to provide metal to metal corners and to weld together all adjoining metal surfaces. The channels 6 of the grids contained in the slabs are, therefore, so set that the reentrant flanges 7 thereof form 35 the external margins of the grid whereby metal to metal corners are provided.

The floor and side wall slabs being thus assembled, the roof slab is placed thereon, as diagrammatically illustrated in Figure 1, and suitably secured to the vertical wall slabs by setting the marginal bracket 41 thereon on the upper margin of the side wall slabs, whereby there will be formed the cubical module or apartment unit.

45 The roof slab is preferably convex on its upper face to facilitate drainage.

The vertical corners of the side walls may be finished as desired. I prefer, however, to provide a corner finish as illustrated in Figure 14. In 50 the form of corner shown, an angle 44 is welded to the contiguous reentrant flanges 7 of the marginal channels 6 of the grid, or the flanges 7 may be bound together by a clamp 45 as shown 55 in Figure 15. There is then inserted in the open marginal edges of the vertical slabs, one or more vertical studs 46, which may be set therein by means of a crane or the like as shown in Figure 1. There is then set thereon a preformed corner 60 plate 47, which may be bound to the margins of the side walls by embedded rods 48 which engage the reentrant flanges 7 of the marginal grid of the side-wall slabs. This corner plate 47 is preferably concave to provide space for 65 leaders or drains 49 for rain water, which are thereby sunk in the corners for attractive architectural effect.

There is preferably provided, at the top of the side wall slab, a flashing 53 of sheet metal, one 70 marginal edge 53, of which is secured to the roof slab and the other marginal edge 51 is seated in a set 57 formed in the upper marginal portion of the side wall, with a lip 54 bent out to form a drip ledge. On the side edges of the roof 75 slab which are formed by the channels 6, the

flashing 53 may be attached within the flange 7 of the channel 6.

A metal gutter 55 of any desired construction, is provided at the marginal edges of the roof slab and the inner marginal lip 56 of the gutter 5 is suitably secured under and within the marginal edges of the roof slab, so that the rain water, melted snow and the like from the roof will be received by the gutter 55 without entering the building or the walls thereof. The gutter is 10 drained by leaders 49 located at the corners of the building.

Modifications in the flashing, gutter, leaders and the like may be made without departing from the spirit of my invention.

As above explained, I prefer to use for the roof a structural slab constructed in the manner above described, but any desired roof means may be provided and I do not intend to limit my invention to any particular roof element.

I have thus described a building module or apartment, the side-walls, floor and roof of which, or one or more of them are prefabricated and comprise a pair of side plates having integrated and contained therein a strengthening 25 and reinforcing grid and insulating material suitably supported against packing, with contained wiring conduits and the like, and which may be embellished or decorated in accordance with architectural designs or individual taste, as 30 indicated in Figure 1. It is obvious that windows and doors are to be provided as may be desired. I do not intend to limit my invention to any particular form of door or window opening but I shall proceed to describe one form which may 35 be used.

Prefabricated windows 57 are preferably provided for the exterior side walls of the building, for the reception of which windows, suitable window apertures are formed in the side wall 40 slabs or panels according to architectural designs, in the manner above described, at predetermined locations.

A preferred form of prefabricated window of the part casement type is illustrated diagrammatically in Figure 16, in which a section 67 is adapted to swing on hinges 67.

In casting the window apertures in the slab unit, the inner face plate 2 of the slab is preferably extended beyond the plane of the outer 50 face plate 1 at the sill margin, as shown in Figure 18 and the face plates 1 and 2 have their marginal edges carried beyond the channels 6, as shown in Figure 17.

The window apertures are preferably lined 55 with a sheet metal lining 60 which is welded to the adjacent channel 6 at 69.

Metal window frames 67 are provided in the window apertures and are preferably surrounded by fibrous insulating tubing 72 embedded in a 60 window encircling filling 73.

The sill portion of the lining of the window apertures, comprises an under sill portion 64 inclined to the horizontal plane, to provide drain means away from the window and which may 65 be welded at 65 to the flange 7 of channel 6 of the side-wall unit. A sill plate 66 is welded to the under sill 64 and has a free marginal edge 67 projecting outwardly, which is preferably lapped back as shown in Figure 18 during erection to protect it against injury. When the erection is completed, this lapped back portion 67 is freed and bent out at approximately a 90° angle to form a water drip beyond the vertical outer plane of the side wall.

The inner margin of the window opening may be finished by a corner plate 71 having a marginal lip 72 which engages the bent over marginal edge of the window lining 60 and sill 66.

5 The opening for the outer door 73 is formed in the slab, constructed as above described, by spacing the channels 6 of the grid, and providing suitable forms for that purpose in the face plates 1 and 2 of the slab in which the door 10 opening is to be made.

10 The door opening is suitably lined and constructed in substantial accordance with the method above described with respect to the window apertures, and is provided with a suitable door 15 sill which is preferably of pre-cast metal.

15 The interior non-bearing partitions may be of much lighter construction than are the outer weight-supporting wall slabs, but they preferably comprise an internal spacing grid integrated and 20 anchored in two face plates and constructed in the manner above described with respect to the outer wall slabs, by casting or molding the face plates and sinking the grid in the same while the face plates are in plastic state and vibrat- 25 ing the same until thoroughly integrated therewith and then curing the face plates, all of which has been fully described above. The interior non-bearing partitions may or may not be provided with the interior insulation as may be de- 30 sired.

35 Seats or slots 74 are preferably cast in the floor slab to receive the base of the interior partitions, as shown in Figure 19.

40 A diagrammatic representation of an interior non-bearing partition is shown in Figure 24, in which the vertical dotted lines represent channels 6 of the grid of the partition wall.

45 The partition wall is seated in its seat or slot 74 preformed in the upper face of the floor slab and the corner or angle between the floor slab and the partition slab may be finished by an angle plate 75. The upper marginal edge of the partition wall is secured to the ceiling or under plate of the roof slab by a mortar seal 76.

50 The doors for the inner non-bearing partitions are preferably of metal or metal facing 77 having mitered corner joints 78. The doors are swung on hinges 82 welded to the channels 6 of the contained grid. The door apertures are lined with metal facing 84 and are preferably provided with metal jambs 85 and suitably finished. The door sills 80 are preferably of wrought metal laid in cement 83.

55 The herein described modules or apartment units are adapted to be used as complete and independent buildings or two or more units may be combined and assembled to form a building comprising plural units. Such assembly may be on the same horizontal plane or one may be 60 erected upon or above another as the individual taste or architectural plans may dictate and when so combined, it is desirable that the joints between adjoining units be concealed and the architectural effect of the building preserved.

65 In joining or combining two or more units, I prefer to provide a single dividing wall therebetween. There is illustrated in Figure 9 a section showing a preferred form of two combined units with a single dividing wall 90 between them.

70 Referring to Figure 9, the dividing wall 90, constructed in accordance with my herein described slab construction and comprising the plates 1 and 2 and grid 1' and channels 6, the contained

insulation not being shown, is erected between the ends of the roof slabs 91 and 92, constructed as above described, and suitably anchored thereto, and the space between the slabs 91 and 92 may be filled with a gutter 93, resting upon and anchored to the respective ends of the adjacent slabs 91 and 92, in which gutter 93 there may be provided a mastic filling 94 or the like. The gutter 93 is preferably welded or otherwise secured to a plate 95 which rests upon the brackets 41 of the two roof slabs 91, 92 and may be welded thereto or may be anchored by means of bolts or pins 96. The lower fragment of Figure 9 shows a like wall construction where the joint between adjoining slabs does not reach the exterior of the building, such as in floors, partitions and the like, in which the two adjacent slabs 97 and 98 are erected upon or against the dividing partition 99 and anchored thereto.

Having thus described my invention, what I claim is:

1. A structural building element comprising two spaced outer plates and a rigid grid therebetween and anchored within the said outer plates, and an insulating filler between the said plates and anchored in the material of which the said plates are composed.

2. In a building, a floor comprising two spaced face plates, a rigid grid between the said face plates and having portions sunk in the said face plates and anchored therein, marginal brackets on the said grid and adapted to rest upon a supporting foundation, in combination with side walls at the marginal edges of the said floor and resting upon the said brackets.

3. In a building, a floor and unitary wall sections at the marginal edges of the said floor and secured thereto, said wall sections comprising respectively two spaced face plates, a rigid grid between said face plates and sunk and anchored therein, and insulating material between said face plates and anchored thereto, and means for attaching said wall sections to said floor.

4. In a building, the combination of a floor, unitary wall sections secured to the marginal portions of the said floor, said wall sections each comprising two spaced face plates and a rigid grid therebetween and anchored in the said face plates, said grid comprising a plurality of metal channels having apertures and a plurality of tangs, cross rods secured to the said channels by said tangs and sunk in said face plates.

5. In a building the combination of a floor, unitary wall sections secured to the marginal portions of the said floor, said wall sections each comprising two spaced face plates and a rigid grid therebetween and sunk in the said face plates, a roof unit supported on the said wall sections, flashing secured to the said roof unit and covering the top edges of the said wall sections, and a gutter supported by the said wall sections and secured to the said roof unit.

6. In a building the combination of a plurality of preformed slabs forming the side walls of the said building, each of the said slabs comprising a pair of face plates and a spacing grid therebetween and anchored therein, a dividing wall in said building and set between the marginal edges of said side wall slabs and secured thereto, said dividing wall comprising a pair of face plates and a spacing grid therebetween and anchored therein.
